MOUNTING FRAME FOR A LOUD-SPEAKER

Paul J. Oslac, Chicago, Ill., assignor to McGregor Electronic Industries, Inc., McGregor, Iowa, a corporation of Delaware

Application February 19, 1957, Serial No. 44,915

Term of patent 14 years

(Cl. D26—14)

FIG. 1

FIG. 2

FIG. 3

FIG. 4

FIG. 5

Fig. 1 is a perspective view of a mounting frame for a loud-speaker embodying my new design;

Fig. 2 is a top plan view of the same;

Fig. 3 is an end elevational view;

Fig. 4 is a bottom plan view; and

Fig. 5 is a side elevation view thereof.

I claim:

The ornamental design for a mounting frame for a loud-speaker, substantially as shown.
